UNITED STATES PATENT OFFICE

131,094

DESIGN FOR A VACUUM CLEANER DUST RECEPTACLE

Vernon E. Carlson, Detroit, Mich., assignor to
Eureka Vacuum Cleaner Company, Detroit,
Mich., a corporation of Michigan

Application May 12, 1941, Serial No. 100,907

Term of patent 14 years

To all whom it may concern:

Be it known that Vernon E. Carlson, a citizen of the United States of America and a resident of Detroit, in the county of Wayne and State of Michigan, has invented a certain new, original, and ornamental Design for a Vacuum Cleaner Dust Receptacle, of which the following is a specification, reference being had to the accompanying drawing, forming a part thereof, wherein:

Fig. 1 is a side elevational view of a vacuum cleaner dust receptacle, embodying my new design;

Fig. 2 is a front elevational view thereof; and

Fig. 3 is a sectional view through the front part thereof and taken in a plane along the line 3—3 of Fig. 2.

The dominant feature of the design consists in providing a substantially flat forwardly presented face along the front of the dust receptacle, such face being illustrated by those portions shown in solid lines on the drawing.

I claim:

The ornamental design for a vacuum cleaner dust receptacle, substantially as shown and described.

VERNON E. CARLSON.
